JAMB ATTACHMENTS FOR WINDOW STRUCTURE

Earl M. Trammell, Sr., and Earl M. Trammell, Jr.,
St. Louis, Mo.

Original application May 11, 1949, Serial No. 92,572,
now Patent No. 2,676,367, dated April 27, 1954. Di-
vided and this application January 28, 1954, Serial No.
406,816

5 Claims. (Cl. 20—52)

This invention relates to improvements in window units, and more particularly to improved framing in and of window units of sliding sash type such as to enhance the ease of sash movement, to improve the sealing qualities of the unit against air and thermal exchange, the improvements being preferably embodied in an improved assembly such as to facilitate manual removal of the sash from the sashway.

Certain of the features of the present assembly are disclosed and claimed in a copending application by these applicants, bearing Serial No. 92,572, filed May 11, 1949, Patent No. 2,676,367 issued April 27, 1954, and entitled "Window Units," of which the present application is a division.

The present developments may be summarized as embodied in a window unit for example one of double hung or horizontal sliding sash type, in which either sash is susceptible of a virtually effortless lifting and lowering or sliding movement, and in which a degree of air-sealing effect is attained which exceeds that of most if not all conventional window units. A further and highly important objective is realized in a window framing which permits easy removal of the sash from, and reapplication to the sashway at any time.

A further object of the invention is realized in a metallic sashway liner over certain of the elements of the sashway structure, and which is designed in furtherance of the purposes stated.

It is an important objective to realize as an article of manufacture a cover or framing element formed of a single strip of metal, and formed to provide a relatively smooth covering over the adjacent jambs of double hung window units, and sill head jambs of horizontal sliding windows. Of further advantage, the cover is inexpensive to manufacture, simple and durable in construction, and adapted to be quickly and easily applied to the sashway of the window unit to afford the several advantages noted above.

An additional and highly valuable objective of the present improvements consists of a snap attachment feature, facilitating attachment of the cover element to a parting bead or the like. Similar provisions may be utilized in other sashway or framing elements such as a resilient weather-sealing element.

The foregoing and many additional objects and advantages of the present improvements will more clearly appear from the following detailed description of a preferred embodiment, particularly when considered in connection with the accompanying drawing, in which:

Fig. 1 is a vertical, partly sectional elevational view taken in a vertical plane in the sashway, with certain of the parts considerably foreshortened, this view showing the location and configuration of recesses and camming portions of the cover element;

Fig. 2 is a fragmentary sectional view taken in a horizontal plane showing the left hand side of the sash assembled in its sashway, and disclosing the structure which constitutes the window framing;

2

Fig. 3 is a fragmentary, sectional elevation, showing the configuration of the recesses formed in the rails, and their relation to the roller fixtures carried by the sash, Fig. 3 being located by line 3—3 of Fig. 2;

Fig. 4 is an enlarged sectional view taken edgewise of a portion of the rail or guide track located at opposite sides of the sashway, Fig. 9 illustrating a camming formation on such track, and

Fig. 5 is a sectional view taken in a horizontal plane showing the configuration of the cover or framing element as disassembled.

Referring now by characters of reference to the drawing, the upper sash is indicated generally at 10 and the lower sash generally designated at 11. Each such sash 15 comprises the usual sash stiles and check rails 14 and 15 (Fig. 1), and the frame elements include the usual inside casing, stool 17, apron 18, and a blind stop 19, and other suitable or usual framing and sash elements, all familiar to those skilled in this art. The window framing further includes a vertical or pulley jamb 21 having a groove or channel 22 into which a parting bead 23 is fixed.

Located at each sashway, is a metal track element 24 provided with a suitable anchorage provision later fully described, such rails 24 being securely assembled 25 in place in vertical position within the sashway. The term "sashway" as employed herein denotes the several channel-forming and frame elements within and along which each sash 10 or 11 is guidedly movable and normally restrained to operation in its own plane. For example, as to the upper sash 10, the sashway is formed by the parting bead 23, pulley jamb 21 and blind stop 19 at each of the opposite vertical margins, together with the transverse or horizontal elements at the ends of the window frame.

35 A plurality of roller fixtures generally indicated at 25 coact with the rails 24. These roller fixtures are preferably located in the regions of the opposite lower and opposite upper margins of each sash. The roller fixtures 40 are structurally and functionally described in detail in our copending divisional application Serial No. 92,572 noted above, but for completeness of disclosure it will be 45 noted that each such fixture includes a roller 28 provided with a V groove 26 engaging a bevelled or apiced rail-ball or roller-engaging head portion provided on each of the rails 25. Certain of the roller fixtures 25 include a leaf spring 27 by which a roller bracket 30 is carried, each spring 27 tending to bias the roller outwardly of the sash.

By preference, each of the upper and lower sash is 50 marginally routed or otherwise recessed to receive the roller fixtures 25. It will be noted that, as described in the noted copending divisional application, certain of the fixtures 25 are of spring type in which the roller 28 is urged or biased outwardly by a leaf spring 27, while 55 certain others of the rollers 28 of the fixtures are not resiliently mounted. It is possible to employ spring-supported roller fixtures throughout, or in other arrangements with non-resilient roller fixtures on the sash.

A clearance is provided considerably exceeding the 60 usual spacing or tolerances in a sliding sash assembly, between the pulley stiles and each adjacent vertical sash stile, this abnormal spacing being provided along at least one, and preferably each of the opposite sides of each sash, as is indicated at 31, and clearance is provided at 65 the sides of the pulley stiles so as to permit depthwise sash displacement.

Fig. 2 discloses the structure of the window framing at the left hand side of the window unit, but it will be readily apparent that the right hand side is identical, being only reversed in position.

For the purpose of permitting removability of the sash, each of the rails 24 on one side of the frame, in the

present example the left hand side (Fig. 2) is provided in particular locations along the sashway, with recessed or cutaway portions 32. There are two such recesses 32, one for each of the rollers 28 on the left hand side (Fig. 2) of each sash, assuming two roller fixtures 25 at this side. The upper pair of recesses 32 serve the lower sash rollers 28. A corresponding pair of cutaway portions 32 in the lower part of the rail 24 serving the upper sash, accommodate, for removal, the rollers 28 of sash 10. These track recesses 32, together with the clearance provided laterally of each of the sash as indicated at 31, enable each of the sash when positioned with its pulleys opposite the companion cutaway portions, to be laterally shifted, i. e. in the plane of the sash and to the left (Fig. 2) to permit sash removal, as will later be described more fully.

For completeness of understanding the full assembly, it may be mentioned, although forming no part of the present improvements per se, that each unit will be provided, with one or more sash counterbalance units (not shown), these being suggested to be of spring type currently available to the trade. These counterbalance units are attached to the respective sash by fixtures providing an automatic captive provision for the counterbalance tape, incident to sash removal. These features and the fixtures by which this result is accomplished, constitute the subject matter of a copending divisional application Serial No. 92,572 filed May 11, 1949 and entitled "Window Units," to which attention is directed for a detailed description of such connectors and fixtures.

As previously noted, the manual removability of either the upper or lower sash 10-11 is provided for when each such sash is moved to a more or less predetermined location in its own sashway. It is most practical to provide a distinct removal zone for each such sash as it approaches its maximum open position. Thus, the upper sash 10 will be brought near a bottom position, and the lower sash 11 will be moved to or near its uppermost position. These particular removal zones assure the normal guided actuation of the sash throughout all or most of its usual range of opening and closing movement. The sash removal provision is identified in part with the track or rail recesses 32 which permit a shifting movement of the sash when the rollers 28 on that side of the sash adjacent the recessed track are brought opposite such recesses 32 whereby to permit the sash to be moved to the left (Fig. 2) to bring the rollers 28 into the recesses 32. The general purpose of the recesses 32 in the track 24 is presently described for better understanding of certain features of a metal jamb cover 33 constituting a valuable feature of the present improvements.

Overlying each of the opposite pulley jambs 21 is a specially formed metal jamb cover 33 which may be provided in strips or rolls as an article of manufacture, and which in preferred form includes a base portion 29 which in effect provides a smooth planar overlay or liner between the pulley jamb 21 and the sash. By preference, the jamb cover 33 is formed of a metal of a non-corroding character, such as anodic aluminum, or aluminum alloy sheet, and may be of rolled or extruded stock. The jamb cover 33 is of such a width that its side margins extend slightly beyond the sashway proper and are either slotted into or gripped between the adjacent elements, for example the member 19 and into a region between pulley jamb 21 and an element of the lower trim of the frame. Thus, the side margins of the strip are concealed.

The primary anchorage of the jamb cover 33 consists of a resilient, intermediate, inverted channel with sides 34, each side 34 including a formed internal bead or reentrant rib 35, each such rib engaging and gripping a conforming groove 36 in the parting bead 23. This interfitting arrangement securely anchors the cover 33.

Secured as by riveting or otherwise through the outer part of the resilient channel portion of cover element 33 just described, is a dust pad indicated at 44 and serving,

when both sash are closed, as a seal between their adjacent marginal portions. This pad 44 forms of itself no part of present improvements, but is mentioned for completeness.

From Fig. 5, it is seen that the base portion 29 of cover element 33 extends laterally outward of sides 34, and assumes an angular or slightly curved configuration in its disassembled form. The resilient sides 34 of the inverted channel are convergently related and the parts of base portion 29 on each side of resilient sides 34 are angularly related to give a curved appearance. When resilient sides 34 are snapped on bead 23, the sides 34 are spread and hence resilient base portion 29, which is normally angularly related (Fig. 5), is held flat against the jamb 21 as is shown in Fig. 2. Because of the normal angular disposition of resilient base portion 29, the cover element 33 is fastened to jamb 21 without the use of any screws or nails. The force exerted on jamb 21 by base portion 29, in its flattened, assembled state (Fig. 2), is sufficient to retain the base portion 29 securely against jamb 21. In order for base portion 29 to exert this retaining force, it is obvious that sides 34 must securely grip bead 23.

A further highly advantageous feature of the present improvements consists in combining, preferably as a one piece structure, a metal track element, such as the described member 24 in each sashway, with the jamb cover 33. It will appear particularly from Fig. 2 that the rail element or guide thus identified is formed by a double folded portion of the body of sheet metal forming the jamb cover 33. The zone of fold, or bight, is, however, so conformed to constitute thereof a rail head or ball 45. This ball or head portion 45 is engaged by the rollers 28; and is shown as of generally triangular sectional shape, the opposite sides of the head presenting a slope of the order of 45 degrees to the plane of the flange or body of the rail 24. It is noted as a preferred structure, to form the rollers 28 with both an inner groove 46 and an outer groove 47, the outer groove 47 conforming substantially in slope to that of the sides of the ball 45 of the rail or track 24, and the inner groove preventing contact of the roller 28 with the apex of the rail 24.

The jamb cover 33, preferably formed of a single piece of metal as noted, is characterized by a further important feature consisting of one or more fixed cam formations 50, the locations of such camming portions 50 being best shown by Fig. 1, and their detail best shown by Fig. 4. Each of these fixed cams 50 consists of a laterally deflected portion of the ball or head of the track in the regions shown, the deflection being an out-of-plane deformation of a short section of the rail in a direction tending to urge the lower sash outwardly of the parting bead 23 and in sealing relation with the jamb cover 33 in this region. In addition, the cams 50 tend to urge the upper sash 10 inwardly or toward the parting bead 23 with a similar weather sealing effect. Thus, when such deflecting cam portions 50 are engaged by the sash rollers 28, the sash is desirably tightened with the noted sealing effects.

From the foregoing it will now have appeared that the jamb cover 33 in its most complete form includes in a single structure the adjacent integral guide rail or track 24; the recesses 32 establishing the zones of sash removal; the resilient self-anchoring assembly including the snap-on feature of the jamb cover 33 identified with its channel and reentrant portions as well as the weather-sealing effects in cooperation with the sash stiles, provided by the camming formation 50.

It is thought that the function of the several portions of the window unit as an assembly, and in particular the metal cover element 33 constituting a portion of the window framing has become fully apparent from the foregoing description of parts. It may be noted for further completeness that, assuming it is desired to remove the upper sash, the sash 10 is moved to a lowered position

so that the rollers 28 on its left hand margin are brought opposite the lower pair of recesses 32, thus enabling a movement of the sash 10 to the left (Fig. 2) with the sash margin brought into the normally unoccupied clearance space 31 of the sashway. This translatory movement is sufficient to cause the right hand side of the sash to clear its track and stops. The right hand edge of the sash 10 may then be brought bodily toward the operator as with a swinging movement, then moved edge-wise or in its own plane to the right (Fig. 2) a distance such that the sash will clear the left hand stops, etc. of the sashway. Reapplication of sash 10 may of course be accomplished by a series of corresponding steps in reverse order from those described for sash removal.

Assuming the lower sash 11 to be in a normal operating relation to its sashway, and that it is desired to remove same as for cleaning or otherwise, the sash 11 is raised to an uppermost position such that its rollers 28 are opposite the pair of track recesses 32 which appear uppermost in Fig. 1. The sash 11 is then moved to the left (Fig. 1) so that the right hand stile of the sash will clear the adjacent frame elements, and may be swung toward the operator, then shifted to the right (Fig. 2), and clear of the sashway. Reapplication of this sash is, now obviously, made by reversing the sequence of steps recited.

It has been pointed out that the counterbalance tapes (not shown) are or may be virtually automatically disconnected incident to the aforesaid removal of sash, and are similarly properly reconnected to the sash upon reinsertion, the counterbalance tapes being held captive when the sash is out of the frame. As noted, the improvements making for this result are fully disclosed in and by copending divisional application Serial No. 92,572.

Although the invention has been described by making a particularized reference to a single preferred embodiment, the detail of description is not to be understood as restrictive, numerous variants being possible within the principles disclosed and within the fair scope of the claims hereunto appended.

We claim as our invention:

1. As an article of manufacture, a length or strip of metal formed to constitute a cover strip overlying portions of a window frame for sliding sash, the cover strip including a longitudinal channel of resilient character, said cover strip having an intermediate portion providing a sash guide rail for coaction with a rail-following element carried by the sash, said guide rail being provided with a depthwise recess therein adapted to clear a rail-following element on the sash.

2. As an article of manufacture, a length or strip of sheet metal formed to constitute a cover overlying a portion of a window frame for sliding sash, the cover strip including a longitudinal channel of resilient character, said cover strip having an intermediate portion providing

a sash guide rail for coaction with a rail-following element carried by the sash, said guide rail being provided with a camming portion deflected out of the normal line of the rail in a direction to urge the rail-following element on the sash in a sash-sealing direction.

3. As an article of manufacture, a metallic cover strip, formed of a single strip of metal, the cover strip being formed to provide a relatively smooth covering over adjacent frame portions of a window unit, the strip constituting the cover being characterized by an intermediate, longitudinal, inverted channel portion, the sides of which are of a resilient character, the cover strip having a portion on each side of said channel portion to provide a metal guide rail, each said guide rail being enlarged to form a rail-ball at its outermost margin, adapted for engagement by a rail-riding element carried by the adjacent sash in assembly, each of said guide rails being further characterized by a camming portion deflected out of the normal line of the rail in a direction to urge the rail-riding element on the sash in a sash-sealing direction, and each said rail further being characterized by a depthwise recess therein adapted to clear the rail-riding element on the sash.

4. As an article of manufacture, a cover element including an inverted channel portion having sides which are of resilient character adapted to receive in gripping relation, a bead element of a window frame, said cover element including a base portion extending laterally outward of said resilient sides, said base portion being normally angularly related to said sides so as to exert a retaining force on an adjacent fixed element of the sashway.

5. In a window unit including frame elements forming a sashway, the frame elements including a bead element and an adjacent jamb element, a cover element including a channel portion having resilient sides adapted to receive the bead element, means selectively attaching the channel portion to said bead element, the cover element including a resilient base portion extending laterally outward of and divergent from said sides and normally angularly inclined toward the said adjacent fixed jamb element, whereby the resilient portion engages the jamb element and exerts a retaining force thereagainst when the channel portion is attached to the bead element.
